WALTER W. WENHOLZ, OF ROCHESTER, NEW YORK, ASSIGNOR TO GENERAL RAILWAY SIGNAL COMPANY, OF ROCHESTER, NEW YORK.

TRAIN CONTROL.

Application filed April 7, 1924. Serial No 704,749.

This invention relates to automatic train control systems for railroads and more particularly to systems of the type commonly known as a continuous inductive track circuit control system.

In one type of continuous inductive control systems to which this invention more particularly relates, alternating current is supplied to the track rails of each block, provided the next block in advance is not occupied, in such a way that this current flows like a track circuit current in opposite directions in the track rails. This track phase, or loop circuit train control current, is detected by suitable receiving coils carried on the locomotive or other railway vehicle in front of the first pair of wheels and axle above the track rails, amplified, and used to control a suitable single phase relay or other electro-responsive device.

In this type of so-called single phase or two-position system, a stray current of the proper frequency and of sufficient magnitude flowing in either track rail will cause false energization of the car relay, and, likewise, unbalanced currents flowing in the same direction in the track rails are liable to cause false energization of the car relay.

One of the principal objects of the present invention is to provide an arrangement and organization of parts in a continuous inductive control system of the single phase or two-position type, in which the car apparatus is protected against false operation by stray currents in the track rails.

The means employed for attaining this object, according to the present invention, affords an additional control or influence which is used to make a set-up on the locomotive, permitting it to travel in so-called "unsignalled" territory, that is, territory not equipped for train control purposes, such as sidings, yard limits, and the like.

Various detailed features, objects and advantages of the invention will be pointed out as the description progresses.

In describing the invention, reference will be made to the accompanying drawing in which: Fig. 1 shows in a simplified and diagrammatic manner the trackway and car apparatus constituting one specific embodiment of the invention, the parts being shown in a manner to facilitate explanation and understanding of the essential characteristics and functions of the invention, rather than to show the particular organization and con-

struction that may be most advantageously employed in practice, and Fig. 2 shows a modified form of trackway apparatus adapted for cooperation with the car-carried apparatus shown in Fig. 1.

60

Referring to the accompanying drawing, for the purposes of explanation, there have been shown two portions of railroad track, one, on the left, representing regular block signal or train control territory, and the other, on the right, representing "unsignalled" or non-control territory. In this instance, the unsignalled territory is presumed to be a portion of track, such as through yards, which is not equipped for automatic train control. It should be understood, of course, that unsignalled or non-control territory is found at various places and under varying conditions in practice. Ordinarily, sidings are not equipped for the automatic control of trains thereon, and this is also true of yard limits, and sometimes terminals. Also, a branch line of the railroad may not be equipped for train control purposes, yet a locomotive fully equipped may run from the equipped territory on the main line on to the branch line. The so-called unsignalled territory may be provided with back circuits and block signals, but not equipped for train control purposes; or, this unsignalled territory may not have any block signals.

70

In the train control or equipped territory, the track rails 1 are divided by insulated joints 2 into blocks in the regular way, one block C, with the adjacent end of another block B being shown. These blocks may be provided with block signals, or the block signals may be omitted and reliance placed upon the cab signals. Semaphore signals S are shown conventionally, without attempting to illustrate their control circuits, which may be of any one of the well-known forms or types.

80

The equipment for each block in train control territory is ordinarily the same; and a description of one will suffice for all. For convenience, the corresponding parts of the different parts of the various blocks are given the same reference numbers with distinctive exponents. Each block is provided with the usual normally closed direct current track circuit, comprising a track relay 3 and a track battery 4. In series with the track battery 4 and its usual adjustable limiting resistance 5, is the secondary of a transformer 6, the primary of which is at times connected across

90

105

110

a transmission line T, energized from a suitable alternator G, preferably of commercial frequency, such as sixty cycles. The typical control circuits for each block in train control territory are shown for the block B, where the circuit for the primary of the corresponding transformer 6 includes a front contact 7 of the track relay 3 of the next block in advance. Instead of the front contact 7 of a track relay, a circuit controller on the corresponding signal S may be used, or other forms of control provided, such that the primary of said transformer is on open circuit when the block next in advance is occupied. It will be observed that, while the train is in a clear block (the next block in advance being unoccupied), alternating current from the transmission line T is supplied through the transformer 6 across the track rails at the exit end of said clear block; whereas in a caution block (a block in the rear of an occupied block) the primary of said transformer is on open circuit and there is no such alternating current flowing in the track rails. The locomotive or other railway vehicle is shown conventionally as comprising a pair of wheels and axle 8, which represent the first or leading pair of wheels and axle of the vehicle. Carried by the vehicle over each of the track rails and in inductive relation thereto, is a receiver or pick-up coil R or R-1. These coils are of the usual construction, with or without iron cores. These receiving coils R and R-1 are preferably tuned to resonance by condensers as shown, and the voltage drop across these condensers is applied to the input circuits of suitable vacuum tube amplifiers A and A-1. These amplifiers are constructed in conformity with recognized principles to amplify the induced voltages produced in receiving coils R and R-1 by the flow of current in the track rails. On the vehicle is a main car relay MR, or other suitable electro-responsive device, which is assumed to be a two-element or polyphase relay of the induction type, using either a vane or a rotor as the movable element and having its contact fingers fastened thereto and biased to a neutral position by counterweights, or the like. One such finger 9 for the relay MR is shown conventionally. One field coil or winding 10 of the relay MR is connected to the output circuit of the amplifier A; and the other field winding 11 of said relay is connected to the output circuit of the other amplifier A-1. For reasons well known by those skilled in the art, the movable element and contact fingers of the relay MR assume one position, conventionally called the normal position and shown in full lines, when both field windings 10-11 are energized by alternating current of the same frequency and having a predetermined phase relation. Since the voltages induced by the regular track phase, or loop circuit train control cur-

rent in the track rails are in time phase, it is necessary to cause phase displacement of the currents produced by such induced voltage so that the relay MR, which is presumed to be one of the induction type, may operate. Such relative phase displacement may be produced in various ways, by the tuning of the receiving coils themselves, by tuning or adjustments in the amplifiers, or by tuning or adjustments in the output circuits of the amplifiers connected to the field windings 10 and 11 of the relay MR. In the form shown, it is assumed that the receiving coils R and R-1 are both tuned to resonance, that there is little, if any, phase displacement in the amplifiers A and A-1 themselves, and that the desired relative phase displacement is obtained by making the circuits for the field windings of the relay MR resistive and reactive. As shown, a resistance 12 is included in the circuit of field winding 10, and an inductive reactance 13 in the circuit for the field winding 11.

The regular train control current flowing in opposite directions in the track rails in a clear block, which for a given instance may be assumed to have instantaneous directional flow as indicated by the arrows a, induces voltages in the receiving coils R and R-1 of such polarity that, when amplified and displaced in phase, the currents in the field windings 10 and 11 of the relay MR produce a torque tending to shift the movable element of said relay and its contact fingers to one extreme position, called the normal or clear position. Upon interruption of this regular train control current, the movable element and contact fingers of the relay MR shift to the neutral or deenergized position, since both field windings 10 and 11 are deenergized. Such flow of train control current is interrupted in a caution block, as previously explained, and also in a block occupied by another train ahead, due to shunting action of the wheels and axles of said forward train. In short, the relay MR is energized normally in a clear block, and is deenergized in a caution or danger block, the finger 9 shifting from the full line position corresponding to a clear indication and to the neutral or vertical position corresponding to a caution or danger indication.

The relay MR may be used to control any suitable or desired form of automatic train control apparatus, controllable by two influences or controls, corresponding to said relay energized to its normal position and deenergized. The particular form of this train control apparatus forms no part of the present invention, and it has been shown diagrammatically and designated K. One suitable form of such apparatus is shown in the patent to Simmen, No. 1,150,309, August 17, 1915. This train control apparatus K is maintained energized and inactive except for a maximum

speed limit, if such is used, so long as the contact finger 9 of the car relay MR is in the normal position. Likewise, a clear or green lamp *g* in multiple with said apparatus K is energized and lighted so long as clear traffic conditions prevail. When the train enters a caution block and the contact finger 9 of the car relay MR drops to the deenergized position, the green lamp *g* is extinguished, the 10 train control apparatus K deenergized and rendered active and a caution or danger lamp *r* energized and lighted. The circuits by which these controls are obtained can be readily traced on the drawings, the conventions B and C being employed to indicate connections to opposite terminals of a suitable source of car-carried energy.

The operation of the train control apparatus K and the cab signal indications just 20 described is merely typical of this type of system; and it should be understood that various other adjuncts and expedients may be utilized.

One important feature of this invention is 25 the protection afforded against false operation of the car relay MR by stray currents in the track rails of the same frequency as the regular train control current. Such stray current may be falsely applied from the 30 transmission line T itself, due to crosses, grounds and the like, or may come from some foreign source of the same frequency, or of a frequency so nearly like the train control frequency that the tuning and receiving coils 35 and amplifiers are not sufficient to avoid operation of the car relay for large values of stray current. Such stray currents ordinarily flow in either one rail alone, or in both rails equally or unequally, but in the same 40 direction for any given instant. If this stray current is in one rail only, it will be evident that the car relay MR will not respond, because only one of its field windings is energized. If such stray current flows in both 45 rails causing said rails to be of the same instantaneous polarity, and the frequency and magnitude of such current is likely to falsely energize the relay MR, such energization causes the relay to operate to its reverse position, since the instantaneous directions of 50 flow of the stray currents are assumed to be the same, whereas the receiving circuits are constructed or adjusted to energize the relay MR normally, only if the instantaneous directions of flow of the currents in the rails 55 are opposite, as indicated by the arrows *a*. Consequently, the relay MR will not be falsely energized to the normal clear position by any stray current in the track rails, such 60 as are at all likely to flow; and this relay will be falsely operated to the clear position only in the remote contingency that the stray currents shall be, not only of the proper frequency and of sufficient strength, but shall 65 also have opposite instantaneous directions.

of flow in the two track rails corresponding to the flow of track phase or loop circuit current.

In view of the foregoing, it will be evident that if a condition is artificially created where 70 the instantaneous directions of flow of the currents in the track rails are the same, the car relay MR will be reversed. Thus, it is possible to obtain an additional control out of the car relay MR by artificially creating 75 such current flow. This may be done by a loop with a sufficient amount of current so that, together with a number of turns, the regular train control or track phase current flowing has its magnetic fields thrown out 80 of balance and given instantaneous magnetic polarities in the same direction. Another way is to supply alternating current of the regular frequency to the track rails in multiple, either with or without the regular track 85 phase current.

This additional control may be utilized for various purposes. In this particular embodiment of the invention, such additional control is employed for obtaining a set-up on the 90 locomotive to permit it to run in unsignalled or unequipped territory. For this purpose, there is provided a normally deenergized stick relay NS on the locomotive, conventionally termed the NS or "no-signal" relay. 95 This NS relay has a pick-up circuit as follows, commencing at B, contact finger 9 of relay MR in the reverse position, wire 14, push button P wires 15 and 16, relay NS, and wire 17 to C. This NS relay has a stick circuit that may be traced as follows: commencing at B, contact finger 9 of the relay MR in the neutral or deenergized position, wire 18, contact finger 19 of relay NS, through its front contact, wires 20 and 16, relay NS and 100 wire 17 to C.

Whenever the contact finger 9 of the relay MR is shifted to the reverse position by any one of the expedients above mentioned, and the push button P is closed, the pick-up circuit for the relay NS is established; and when said contact finger 9 drops to the deenergized position, a stick circuit for said relay is established. The relay NS is preferably made slow releasing, so as not to drop away during the interval between the opening of the reverse contact and the closing of the deenergized contact of the main car relay. 110

The relay NS when energized is assumed to provide the controls necessary to permit the 120 locomotive to travel in unequipped territory. For instance, the train control apparatus K is maintained energized, the caution or danger cab signal or indicator *r*, extinguished, even though the relay MR is deenergized due 125 to the absence of train control current, and a distinctive indicator or cab signal NS^a is illuminated to advise the engineer the train is traveling in unequipped territory.

It will be observed that the set-up for un- 130

signalled territory is obtained by temporarily reversing the car relay MR just prior to the entrance of the train into the unequipped territory, the engineer operating the push button P, thereby picking up the NS relay, which is stuck up when the main car relay MR drops upon the entrance of the train into the unequipped territory and is maintained energized so long as the train travels in such unequipped territory. Upon entrance into signalled or equipped territory, a permanently active loop or track section may be employed to operate the relay MR to its normal position, so as to deenergize the NS relay; or, reliance may be placed upon the fact that as soon as the train enters a clear block, the relay MR is energized and for this reason the NS relay is deenergized.

Referring to the accompanying drawing, one way of providing the set-up on the locomotive for unsignalled territory is shown in connection with the track section D beginning at the exit end of the block C, it being assumed that the unsignalled or non-control territory begins at the exit end of the block C, while the train is running in unequipped or unsignalled territory, the engineer is supposed to be responsible for the safety of the train, relying upon train orders, block signals (if these are used), or similar safe-guards, the same as trains are ordinarily being operated without automatic train control. Until the train actually enters unsignalled territory, however, it is considered that the engineer is justified in relying upon the automatic train control system, including the indications of the cab signals. For this reason, the regular train control current for the block C, which is supplied from the transformer 6 at the exit end of this block, is preferably cut off if there is a train within braking distance for the normal running speed beyond the exit end of the block C. As shown, the primary of the transformer 6 for the block C is controlled by a line relay LR, which has its energizing circuit taken through front contacts of a track relay 3¹ for the track section D and a track relay 3² for another track section E immediately in advance of the section D, the combined length of the track sections D and E being equal to or greater than such breaking distance. In view of this control, the engineer while running through the block C under a clear signal, may assume that there is no train within braking distance of the end of train control territory. The indications of the signal S at the entrance to the block C is preferably also made dependent upon the line relay LR, so that this signal indicates caution if there is a train present in track section D or E.

The track section D is relatively short, say 100 feet or less, and is merely long enough to assure time for the operation of setting up the unsignalled territory control upon a

locomotive passing over this track section at speed. It will be observed that the track section D is provided with a track battery 4¹, transformer 6¹, and track relay 3¹, the same as a block in regular train control or signal territory, except that the primary of the transformer 6¹ is connected directly across the transmission line T and is not traffic controlled. In other words, the alternating current for train control purposes is always present on the track rails for the track section D.

As previously explained, the energization of the NS relay on the car is accomplished by reversing the instantaneous relative directions of flow of the currents in the track rails. As shown, this is accomplished for the track section D by a loop L. This loop L is made of wire or cable, well insulated and suitably armoured and protected, and as shown comprises two turns. Two sides of this loop are disposed closely to one of the track rails (the upper track rail as shown), preferably by being secured to the web of the rail underneath the head. The other side of the loop L is disposed at some distance from the railroad track, far enough so that the magnetic field created by current therein will not materially influence the receiving coils R and R-1. This loop L is so connected that the currents in the sides of the loop adjacent to one track rail will have for a given instant a direction of flow or polarity, indicated by the arrows b, opposite to the instantaneous direction of current flow in the adjacent track rail, indicated by the arrow a, supplied from the transformer 6¹. Since this loop L is in series with the primary of the transformer 6¹, it is assured that, whenever there is current flowing in the track rails of the track section D there will be current in this loop. As shown, it is assumed that each turn of the loop L carries as much current as each track rail of the section D; but it is obvious that a larger or smaller number of turns may be used as desired, so long as the combined magnetic fields have the desired values and polarities. Of course, the currents in said loop and track rails should have the same phase relation.

With such an organization of trackway equipment as just described, the car relay MR is caused to shift to the reverse position when the car enters the track section D, because the magnetic fields due to currents flowing in the track rails and in the loop L respectively have instantaneous magnetic polarities reverse from that of the magnetic fields extending over the track rails in regular train control territory. In regular equipped territory, the currents in the two track rails, and likewise the resultant magnetic fields over the two rails, are of opposite instantaneous polarity, as indicated by the arrows a. In the track section D, however, the current in the loop L, indicated by the arrows b for the instant in

question, over-balances the current a in the adjacent track rail, giving the resultant, so far as the receiver R is concerned, of current flowing in this track rail of the same instantaneous direction of flow as that flowing in the other track rail.

A similar reversing of relative instantaneous direction of flow of current in one of the rails for the track section D may be obtained by supplying current which flows in the track rails of this section in multiple; and this may be easily accomplished by connecting a balancing resistance 24 across the track rails at each end of this section and connecting their middle points to the transmission line through a suitable transformer 25, as shown in Fig. 2 of the drawings. Other ways of accomplishing the same result are possible, and may be suitable under some certain of the varying conditions encountered in practice.

In disclosing the nature of this invention, attention has been primarily restricted to one specific form, which has also been illustrated in a simplified and diagrammatic manner. It should be understood, however, that the invention is not restricted to the particular construction and arrangement of parts and circuits shown and described, but is susceptible of considerable modification, adaptation and addition. I desire to have it understood, therefore, that I include within the scope of this invention all modifications and adaptations, in so far as they may fairly come within the scope of the appended claims, with the terms of these claims broadly interpreted in the light of the purposes and function herein explained.

What I claim is:—

1. A train control system of the continuous inductive control type for railroads provided with blocks comprising, means associated with each block for impressing across the track rails at the exit end thereof an alternating current voltage only if the block next in advance is unoccupied, receiving coils on a vehicle in front of the first pair of wheels and axles thereof and disposed over the track rails in inductive relation thereto, a two-element relay of the induction type on the vehicle having its field windings connected separately to said receiving coils, and means for causing relative phase displacement of the currents of said field windings with respect to the induced voltage in the receiving coils.

2. In a train control system, the combination with traffic controlled means for impressing an alternating current voltage across the track rails, whereby current of opposite instantaneous directional flow is present in the track rails in front of a railway vehicle, of a polyphase relay on the vehicle, amplifiers, and separate receiving coils on the vehicle, said relay being operated in one direction by said current of opposite instantaneous directional flow and in the reverse direction by currents

flowing in the same direction at the same instant.

3. Locomotive equipment for train control systems of the continuous inductive type comprising, receiving coils carried in front of the first pair of wheels and axle of the locomotive, one over each track rail in inductive relation thereto, said receiving coils being magnetically separate, amplifiers having their input circuits connected to said coils, and a two-element relay of the induction type having its field windings connected separately to the output circuits of said amplifiers, there being relative phase displacement of the currents in the field windings of said relay for voltages of the same time phase induced in the receiving coils whereby to operate the said relay by current flowing in a single track circuit.

4. In a train control system of the continuous inductive type, a three-position alternating current relay on a car, and means including receiving elements disposed only in front of the first pair of wheels and axles of the car for operating said relay either to one or to the other of its energized positions depending upon whether the instantaneous directions of flow of the alternating currents in the two track rails are in the same direction in the two rails or the flow of current in one rail is in one direction and the flow of current in the other rail is in the opposite direction at a given instant.

5. In a train control system of the two position continuous inductive type; in combination with vehicle-carried means including a three-position relay of the two coil type on the vehicle, inductive influence receiving means disposed over each of the two track rails in front of the first axle of the vehicle one of which is connected to one coil of said relay and the other of which is connected to the other coil, said relay assuming an energized position only if both of said coils are energized by current, said relay also moving a contact in one direction if the flow of currents in the coils have a certain directional relation and moving the contact in the opposite direction if the relative flow of currents in the two coils is reversed; and of trackway means for causing the flow of train control current down one rail through the axles of said vehicle and back through the other rail only in the block occupied by the vehicle, if a portion of the block in advance of said vehicle and the next block in advance thereof are not occupied by another train, said flow of current down one rail and back through the other acting on said influence receiving means to cause said relay to assume a normal energized position, and means for restricting the movement of the train if said relay changes from its normal position.

6. In a train control system of the continuous inductive type, with separate receiv-

ing coils carried on a railway vehicle in front of its first pair of wheels and axle, one coil being disposed over each of the two track rails and in inductive relation thereto, electro-responsive means on the vehicle connected to said coils, said electro-responsive means being operated differently for different relative instantaneous directions of flow of alternating current in but one trackway circuit in the two track rails.

7. In a train control system, the combination with a block provided with a track relay, of means for supplying an alternating current voltage across the track rails at the exit end of said block, thereby causing a flow of alternating current in the track rails in opposite instantaneous directions in front of a vehicle in said block, and electro-responsive means on the vehicle energized to one position if such flow of alternating current only exists and to a different position if currents flowing in said track rails in the same direction at a given instant only exist.

8. In a train control system of the continuous inductive type, a pair of receiving coils carried on a vehicle in front of its first pair of wheels and axle and disposed in inductive relation separately to the track rails, a polyphase relay on the vehicle, and separate amplifying means on the vehicle connecting said receiving coils independently to the field windings of said relay and producing in said field windings amplified currents relatively displaced in phase for voltages of the same time-phase relation which are induced in said coils by flow of alternating current in the track rails whereby the polyphase relay is operable by current flowing through a single track circuit.

40 9. Receiving equipment for continuous inductive train control systems, comprising two separate receiving coils on the vehicle in front of its first pair of wheels and axle, separate amplifiers connected to said coils, and a polyphase relay having its field windings coupled to the output circuits of said amplifiers, said relay assuming one energized position if current flowing in opposite directions in the track rails at a given instant only exists and assuming the other energized position if currents flowing in the track rails in the same direction only exist.

10. In a train control system, for railways having territory equipped for train control purposes and territory not equipped for train control purposes, the combination with car equipment comprising receivers carried only in front of the first pair of wheels and axle, a three-position relay on the car, means for operating said relay to either its deenergized position or one of its energized positions depending upon traffic conditions while the car is traveling in equipped territory, and means for operating said relay to its other energized

position when the car enters unequipped territory.

11. In a train control system of the continuous inductive type, in combination, car receiving apparatus including two separate receiving coils carried in front of the first pair of wheels and axle in inductive relation to the track rails, separate amplifiers connected to said coils, a polyphase relay coupled to the output circuits of said amplifiers, said relay assuming one energized position if current flows in the track rails in opposite directions only at a given instant, assuming the reverse energized position if currents flow in the track rails in the same direction only at a given instant and assuming the de-energized position if there is current flowing only in one of the rails or there is no current flowing in the rails.

12. In a train control system of the type described, the combination with car apparatus comprising, two receiving coils in front of the car, two amplifiers, a polyphase relay having its field windings separately energized by currents derived from said amplifiers resulting from voltages induced in said receiving coils, said relay assuming a normal energized condition in response to voltages induced in said receiving coils by current flowing in opposite directions adjacent said coils and assuming a reverse energized condition for voltages in said receiving coils corresponding to the flow of currents in the same direction adjacent said coils.

13. In a train control system, the combination with a car-carried three-position polyphase relay responsive distinctly to voltages induced by magnetic fields corresponding to the flow of instantaneous alternating current in opposite directions in the track rails alone and to the flow of instantaneous alternating current in the same direction in the track rails alone, of means for supplying alternating current to the track rails flowing in opposite directions at a given instant under safe traffic conditions only for operating said relay to one energized position, and means at predetermined points along the track constituting a current conducting path and when energized producing a magnetic field combined with the field produced by such flow of current in one of the track rails to give resultant magnetic fields corresponding to the flow of current in the same direction in the two track rails at a given instant, whereby said relay is operated to a different energized position.

14. In a train control system of the type described, in combination with a car-carried three-position polyphase relay, of means on the car and on the track cooperating inductively through an intervening air-gap at all points in the travel of the car in certain territory to cause said relay to assume one of

- its energized positions under favorable traffic conditions due only to the flow of alternating current in the track rails flowing in opposite directions at a given instant, said relay being caused to assume its other energized position in other territory by effects corresponding only to flow of alternating current in the track rails in the same direction at a given instant.
15. In a train control system of the continuous inductive type, in combination with a car-carried three-position relay of the two-element induction type, of cooperating means on the car and on the trackway acting inductively through an intervening air-gap to cause said relay to assume one or the other of its energized positions, depending alone upon the flow of alternating currents in the same direction in the two track rails at a given instant and alone on the flow of alternating current in opposite directions in the two track rails at a given instant, respectively.
16. In a train control system of the continuous inductive type, receiving means on a vehicle including a three-position polyphase relay operated to one energized position by alternating current flowing in track rails ahead of the vehicle in opposite directions in the two rails at a given instant, said relay not being operated to said energized position by flow of stray currents in the same direction in the track rails nor by the flow of stray current in one rail only.
17. A system of the type described in combination with circuits on the trackway including the track rails and energized so as to cause alternating current to flow in opposite directions in said rails at a given instant under safe traffic conditions only, electro-responsive means on a vehicle controlled inductively through an intervening air-gap by the flow of current in said trackway circuits and operable to its clear condition only by such flow of current in opposite directions in the track rails, whereby said relay is not falsely operated to the clear condition by the flow of stray current in one track rail or by the flow of stray current in both of the track rails in the same direction.
18. A train control system of the continuous inductive single phase or two-position type comprising, a polyphase alternating current relay on the vehicle, means on the vehicle for causing said relay to assume the normal energized position in response to the flow of a single alternating current flowing down one rail and back through the other rail and for causing the relay to assume the other and reverse energized position in response to the flow of alternating currents flowing down the two rails substantially in phase with each other, and which will allow the relay to assume its de-energized position if there is an alternating current flowing in one rail only, and means for restricting the movement of the train when said relay assumes either the reverse or the de-energized position.
19. A train control system according to claim 18 adapted for use in systems where in only part of the territory is equipped for train control purposes further comprising, a non-control territory electro-responsive device which if in its active energized position permits the train to proceed even though the polyphase relay is de-energized and having a pick-up circuit and a stick circuit, a push button which if depressed closes a break in said pick-up circuit, said pick-up circuit including contacts closed only when said polyphase relay is in its reverse energized position and said stick circuit including contacts closed only if said polyphase relay is de-energized.
20. Car-carried apparatus for automatic train control systems of the single phase alternating current continuous inductive type comprising, a polyphase relay, means inductively associated with one of the track rails on which the car travels connected to one element of the polyphase relay, means inductively associated with the other track rail and connected to the other element of said relay, said two means and relay being so constructed and correlated that flow of alternating current in phase opposition in the two track rails causes said relay to assume one energized position and the flow of alternating currents substantially in time phase in the two track rails causes said relay to assume the reverse energized position, and means for restricting the movement of the train if said relay assumes the reversed or the de-energized position.
21. A train control system according to claim 20 adapted for use in system wherein only part of the territory is equipped for train control purposes further comprising, a non-control territory electro-responsive device which if in its active energized position permits the train to proceed even though the polyphase relay is de-energized and having a pick-up circuit and a stick circuit, a push button which if depressed closes a break in said pick-up circuit, said pick-up circuit including contacts closed only when said polyphase relay is in its reverse energized position and said stick circuit including contacts closed only if said polyphase relay is deenergized.
22. In combination, a railway, a source of alternating current at times connected across the track rails thereof, two train carried windings in inductive relation with the two track rails respectively, a train carried relay device comprising two coils, means for energizing one of said coils solely by one of said windings and the other coil solely by the other of said windings, said relay device also comprising a contact which is closed when

said windings are energized by alternating current flowing through the track rails in series but not by alternating current flowing through the track rails in multiple or in one rail alone, and train governing mechanism controlled by said contact.

23. In combination, a railway, a source of alternating current connected across the track rails thereof, two train carried windings in inductive relation with said two track rails respectively, a contact controlled solely by said two windings and closed when both windings are energized but not when either winding alone is energized, and train governing mechanism controlled by said contact.

24. In combination, a railway, a source of alternating current connected across the track rails thereof, two train carried windings in inductive relation with said two track rails respectively, and train governing mechanism controlled solely by said windings and responsive to energization of both windings but not to energization of either winding alone.

25. In a train control system of the continuous inductive type, with separate receiving coils carried on a railway vehicle in front

of its first pair of wheels and axle, one coil being disposed over each of the two track rails respectively and in inductive relation thereto, electro-responsive means on the vehicle connected to said coils, said electro-responsive means being operated differently for current flowing in the same direction in two rails than for current flowing in the opposite direction in the two track rails.

26. In combination, a railway track, means for supplying said track with alternating train controlling current which flows through the two rails in series, means for supplying the track with alternating current which flows through the two track rails in multiple, a train carried alternating current relay having two windings controlled by the currents in the two track rails respectively whereby the relay is energized in normal direction when current flows through the rails in series and in reverse direction when current flows through the rails in multiple, and train carried governing mechanism controlled by said relay.

In testimony whereof I affix my signature.

WALTER W. WENHOLZ
